UNITED STATES PATENT OFFICE

137,475

DESIGN FOR A PICTURE FRAME

James A. Morehead, Huntington, W. Va., assignor to Sinclair Glass Company, Ceredo, W. Va., a corporation of West Virginia

Application January 31, 1944, Serial No. 112,376

Term of patent 7 years

To all whom it may concern:

Be it known that I, James A. Morehead, a citizen of the United States, residing at Huntington, in the county of Wayne and State of West Virginia, have invented a new, original, and ornamental Design for a Picture Frame, of which the following is a specification, reference being had to the accompanying drawing, forming a part thereof.

The essential features of my design reside in the parts shown in full lines.

I claim:

The ornamental design for a picture frame, substantially as shown and described.

JAMES A. MOREHEAD.
